UNITED STATES PATENT OFFICE.

ROBERT G. GLEAVES, OF GREENBRIER, TENNESSEE.

SELF-LOCKING COVER FOR GRAVE-VAULTS.

1,267,759.

Specification of Letters Patent. Patented May 28, 1918.

Application filed July 31, 1917. Serial No. 183,706.

To all whom it may concern:

Be it known that I, ROBERT G. GLEAVES, a citizen of the United States, residing at Greenbrier, in the county of Robertson and State of Tennessee, have invented certain new and useful Improvements in Self-Locking Covers for Grave-Vaults, of which the following is a specification.

My invention relates to new and useful improvements in burial vault covers and has for its primary object the provision of a vault cover of metal or equivalent material so formed that it does not rest upon the box in closing the casket but is spaced above it to support the earth filling the grave.

Masonry or stone vaults are too expensive for general use and the custom at present is to dig a grave in which the vault or casket box receiving portion is equal in depth to the height of the box and in which the vault is narrower than the remainder of the grave so that shoulders are provided along either side of the vault. With a grave thus prepared after the casket, inclosed in its box, is lowered into the vault, a covering of boards is positioned over the box resting upon these boards. These boards, however, soon rot away and permit caving or settling of the earth above the grave. One aim of this invention resides in the provision of a transversely arched metallic cover adapted to rest at its side edges upon the shoulders at the sides of the vault with its intermediate portion spaced above the casket containing box and forming a strong and durable support for the earth filling the grave.

In this connection, a still further object of my invention resides in means for locking the cover to the box containing the casket which will not only prevent lateral displacement of the cover with respect to the box but which will prevent unauthorized removal of the box as in order to remove the box it will be necessary to remove all the earth over the cover and to then lift both the cover and box which can hardly be done without the use of blocks and tackle or equivalent devices.

A still further object of my invention resides in constructing a cover of the above described character which shall be not only efficient as regards protecting the box and

its inclosed casket, but which shall be cheap in construction and therefore within the reach of all.

With these and other objects in view, my invention will be more fully described, illustrated in the accompanying drawings and then specifically pointed out in the claims which form a part of this application.

In the drawings:

Figure 1 is a vertical sectional view taken through one end of a grave showing the casket containing box in elevation and the adjacent end of the cover in section;

Fig. 2 is a longitudinal sectional view taken through the grave showing the cover in section and the box in elevation;

Fig. 3 is a fragmentary perspective view of one end of the cover and one end of the casket inclosing box showing the lock between them;

Fig. 4 is a sectional view through the lock supporting portion of the cover and through the lock engaging eye of the box, the lock being shown released.

Corresponding and like parts are referred to in the following description and indicated in all the views of the drawings by the same reference characters.

In order to insure a clear and accurate understanding of my invention, I have illustrated it to show the manner in which it is employed. Referring particularly to Figs. 1 and 2 of the drawings, I have disclosed a grave 10 constructed in the usual manner and inclosing the usual casket containing box 11 having the usual cover 12. The vault portion 13 of the grave, as is customary, is equal in depth to the height of the box 11 and narrower than the main body of the grave so that longitudinal shoulders 14 are provided at the sides of the vault.

My invention resides in providing a cover for the vault which will rest upon the shoulders 14 and not upon the box 11 and which may, if desired, have locking engagement with the box 11.

This cover 15 is substantially rectangular in shape, is preferably formed of relatively heavy sheet metal or equivalent material, and is arched transversely throughout its length. Preferably also it is transversely corrugated, as shown at 16, for added

strength. As clearly shown in Figs. 1 and 2 of the drawings, this vault cover is proportioned to extend throughout the length of the grave and to rest at its longitudinal edges upon the shoulders 14 so that its arched portion will be spaced above the box 11.

Obviously, with the vault protected by a cover of this character, which is substantially indestructible, all pressure of earth in the grave above the vault is supported by the cover and the box and inclosed casket are protected.

Preferably, however, I provide locking devices 17 for securing the end portions of the cover to the ends of the box 11 so as to not only hold the cover against any possible lateral movement but to also prevent removal of the box and inclosed casket from the grave by unauthorized persons, it being obvious that if the cover is locked to the box all the earth above the cover must be removed before access may be had to the vault and the locks not being readily accessible the cover and box must be simultaneously lifted. Such an operation would require considerable time and proper apparatus for hoisting the box and cover from the grave so that a cover locked to the box practically protects the grave from robbery.

My improved locking device 17 includes a supporting body 18 curved longitudinally to correspond to the curvature of the under face of the cover 15 and secured to the cover by rivets 19 or other suitable fastening devices. The lower face of this body 15 is recessed to receive the upper ends of the latches or locking dogs 20 which are secured to the body by pivots 21. The outer side edges of these latches are formed with locking seats or notches 21 and their ends are beveled, as shown at 22. A leaf spring 23 secured between the latches serves to hold them away from each other, as clearly shown in Fig. 4. Coöoperating with these latches are keepers 24 which are secured one to each end of the casket inclosing box 11, preferably midway of its width and near its top. These keepers each include a substantially U-shaped body portion having lateral ears 25 at its free end for attachment to the box and having its side portions diverging upwardly, as shown at 26, to correspond to the inclined faces of the locking seats 21.

As best shown in Fig. 2, one of the locking devices 17 is secured to the under face of the cover at each end so that when the cover is lowered in place the locking dogs or latches will pass through the keepers, the sides of which will engage in the locking seats to automatically secure the cover in place, the springs, of course, holding the locking dogs or latches in close engagement with the sides of the keepers.

Although I have described my invention in all its details I do not wish to be limited to the specific construction shown but reserve the right to make any changes which may fall within the scope of the claims.

For instance, the cover may be used with or without the locks and it may be made to rest upon or rest upon and be locked to the box even when it is not convenient to dig a vault to provide the shoulders which ordinarily support the cover.

Having thus described the invention, what is claimed as new is:

1. In a grave vault cover, the combination with a burial box, of a transversely arched vault cover of greater width than the box, a pair of latch dogs pivotally supported from the underface of the vault cover adjacent each end with their outer faces formed with locking notches, strings secured to the dogs and normally tending to hold the dogs of each pair away from each other, and keeper eyes secured to the ends of the box and adapted to receive the locking dogs whereby the vault cover will be locked to the box.

2. In a grave vault cover, the combination with a burial box, of a vault cover, and means for automatically locking the vault cover in position above the box and to the box, said locking means being disposed wholly below the cover and the cover being of greater dimensions than the box.

3. In a grave, the combination with a chamber proportioned to closely receive a burial box and an upper chamber wider than the first chamber to provide shoulders at the sides of the first chamber, of a burial box within the first chamber, a vault cover engaging at its longitudinal edges upon the shoulders with its intermediate portion spaced above the box and connecting means between the box and cover.

4. In a grave, the combination with a chamber proportioned to closely receive a burial box and an upper chamber wider than the first chamber to provide shoulders at the sides of the first chamber, of a burial box within the first chamber, a transversely upwardly arched vault cover engaging at its longitudinal edges upon the shoulders with its intermediate portion spaced above the box, and locking means between the vault cover and the box whereby the vault cover can be removed only with the box.

5. In a grave, the combination with a chamber proportioned to closely receive a burial box and an upper chamber wider than the first chamber to provide shoulders at the sides of the first chamber, of a burial box within the first chamber, a transversely upwardly arched vault cover engaging at its longitudinal edges upon the shoulders with its intermediate portion spaced above the

box, and locking means between the vault cover and the box whereby the vault cover can be removed only with the box, said locking means consisting of keepers at the ends 5 of the box and latches adapted to automatically engage the keepers upon lowering of the vault cover into place.

6. The combination with a burial box, of a vault cover, and coacting means upon the cover and box for locking the cover to the 10 box at various positions of elevation above the box.

In testimony whereof I affix my signature.
ROBERT G. GLEAVES.
